UNITED STATES PATENT OFFICE.

ALFRED G. F. KUROWSKI, OF BROOKLYN, NEW YORK, ASSIGNOR TO UNDERWOOD
TYPEWRITER COMPANY, OF NEW YORK, N. Y., A CORPORATION OF DELAWARE.

TYPEWRITING MACHINE.

Application filed January 27, 1921. Serial No. 440,320.

To all whom it may concern:

Be it known that I, ALFRED G. F. KUROWSKI, a citizen of the United States, residing in Brooklyn Borough, in the county of 5 Kings, city and State of New York, have invented certain new and useful Improvements 10 in Typewriting Machines, of which the following is a specification.

This invention relates to line-locking and 15 signalling mechanisms for typewriting machines, and is an improvement on the device disclosed in the application of George W. Campbell, Serial No. 240,146, filed June 15, 1918, which became Patent No. 1,407,982, 20 dated February 28, 1922. The invention is shown as applied to an Underwood portable typewriter.

It is an object of this invention to provide 25 a simple structure for line-locking and signalling, which cannot be accidentally set. To this end, a margin-gage or stop is adjustably mounted on a rod journaled in the shift-frame of the machine, said rod being provided with fixed arms. A member having 30 a double cam surface is mounted on the carriage, one of said cams being adapted to cooperate with the margin-stop to operate one of said fixed arms to actuate a signalling device, and the other cam surface being adapted to co-operate with the margin-stop to 35 operate another of said arms to actuate a line-locking mechanism.

A further feature of this invention is the provision of novel line-locking and signalling mechanisms.

Other features and advantages will hereinafter appear.

In the accompanying drawings,

Figure 1 is a sectional side view of a typewriting machine, showing the invention applied thereto.

Figure 2 is a plan view of the device shown in Figure 1, parts being omitted and broken away to show the underlying structure.

Figure 3 is a detail plan view of a margin-stop engaging the member having the double cam surface.

Figure 4 is a rear perspective view vertically foreshortened, showing the signalling and line-locking devices and several co-operating elements.

Figure 5 is a detail, in side elevation, of the signalling mechanism.

Figure 6 is a detail, in rear elevation, 55 partly sectioned, of a margin-stop.

Figure 7 is a plan view of the machine, showing mainly the line-locking mechanism in effective position.

Figure 8 is a detail sectional view, 60 showing the relation of the line-locking lever in effective position, the universal bar, and a type-key.

Type-keys 10 actuate bell-crank 11 and links 12, to swing type-bars 13 upwardly 65 and rearwardly against platen 14, mounted for rotation in a carriage 15. Said carriage is mounted to travel on a case-shift frame 20, shiftable by the depression of shift-keys 22. The carriage is adapted to travel from 70 right to left in a letter-feeding direction at the actuation of the type-keys, which operate a universal bar 23 mounted in the main frame of the machine, and which, in turn, operates escapement mechanism, indicated at 75 24, which controls the feeding of the carriage.

Upon a rear bar 30 of the carriage is pivotally mounted at 31 a lever 32, carrying a double cam-member 33 at one end and a 80 finger-piece 34 at the other end. A spring 35 normally presses member 33 downwardly, but the downward movement is limited by a stop-pin 36 contacting with the upper edge of lever 32.

A rod 40, flattened on its top surface, and provided with graduations corresponding to line-spaces on said flattened surface, is journaled in the end walls 41 of the shift-frame 90 20.

Slidable along said rod are margin-stops 42, provided with finger-pieces 43 adapted to be depressed against the action of a spring 46 to release pawls 47 from engagement with teeth 50 on the underside of the rod 40, enabling the stops to be slid along 95 the rod to any desired positions. Each margin-stop is provided with a projection 44, 45. The rod is so mounted that the projection 44 engages the cam-member 33 at the first cam surface 51 as the carriage travels 100 toward the left. Upon further travel toward the left, the projection 44 engages the second cam surface 52, and still further travel to the left brings projection 44 against a projection 53 on the cam-member to prevent further travel of the carriage toward the left. When the carriage is retracted, its travel toward the right is limited by the

85

90

95

100

105

contact of projection 53 with projection 45. When it is desired to write beyond the limits set by the stops 42, the finger-piece 34 is depressed, to raise the cam-member 33 to release the latter from contact with projection 44 or 45 of the stops.

When projection 44 rides upon cam 51, the cam exerts a leverage upon the margin-stop (see Figure 1) and rotates rod 40. 10 Fixed to one end of rod 40 is an arm 60, which projects along the side of the shift-frame to a bell 61 fixed to said frame. Pivotally mounted on said frame at 62 is a lever 63 having a clapper-portion 64 bent inwardly to lie within the surface of the bell. A lever 65 is pivoted to lever 63 at 15 66, and is provided with an overlapping portion 67 normally held against the upper surface of lever 63 by a spring 68. The tip 20 of arm 60 normally lies beneath the tip of lever 65, and projects a short distance thereunder (see Figure 1). When projection 44 comes in contact with cam surface 51 and rotates the rod 40, the arm 60 is swung upwardly and carries with it lever 65. It is apparent that lever 63 must move upwardly integrally with lever 65. The movement of arm 60 is such as to carry it beyond the tip of lever 65, allowing the spring 68 to 25 snap levers 63 and 65 back to normal, clapper 64 striking bell 61 on the return stroke. A stop 69 limits the return movement of the levers.

Upon further travel of the carriage to the 30 left, the projection 44 rides upon cam surface 52, rotating rod 40 to a greater degree than when said projection was in contact with cam surface 51. Arm 60, being held in position above lever 65, performs no additional function upon being further raised. To the other end of rod 40 is fixed a second arm 70, which performs no function when raised by the contact of projection 44 with cam surface 51; but when said projection 35 rides upon cam surface 52, the end 71 of arm 70 contacts with a substantially vertical cam surface 72 (see Figure 7), forming the end of a bent arm 73, fixed to an arm or lever 74 intermediate the length thereof. Said lever 74 is pivotally mounted at 40 on the main frame of the machine, and its end is normally lodged by a spring 80 in a slot 76 in a bar 77 fixed to the machine, said slot 45 being adjacent and just below the universal bar 23. As end 71 rides up on cam surface 72, arm 73, and hence arm 74, is rotated to swing the end of arm 74 beneath the universal bar and prevent actuation thereof by any type-key, as in Figures 7 and 8. The cam 50 surface 72 is of such height as to insure contact between said surface and the end 71 when the carriage is in upper or lower case position. It will be observed from Figure 7 that the end of arm 74 is supported partly 55 or wholly in the slot 76 at all times. The

arm 74 may, therefore, be made of light metal without possibility of bending when the universal bar is pressed down in contact therewith. It will be noted that the arms 73 and 74, taken together, form a bell-crank 70 lever.

The lever 74 of the key-locking mechanism and the arm 60 of the signalling mechanism may be returned to normal, by the spring 80, by retracting the carriage to its 75 initial position at the right, or by depressing finger-piece 34 to break the contact between projection 44 and the cam member. The rod 40 returns to normal position, carrying with it arms 60 and 70, a retractile spring 81, connected to the shift-frame and to the arm 70 (Figure 1), being provided for this purpose. The tip of arm 60 depresses the tip of lever 65, and swings past the latter, whereupon the spring 68 snaps the lever 65 back to 80 normal.

Variations may be resorted to within the scope of the invention, and portions of the improvements may be used without others.

Having thus described my invention, I 90 claim:

1. In a typewriting machine, the combination of a shiftable frame, a carriage mounted to travel in said frame, a rod journaled in said frame, a margin-gage device mounted on said rod, a projection on said margin-gage device, arms fixed to said rod, one at each end thereof, a bell-ringing device mounted on said frame, a key-locking mechanism mounted on the machine, and a member on said carriage having a double cam surface adapted to engage said projection, the engagement of said projection with one of said cams serving to rotate said rod to cause one of said arms to operate the bell-ringing device, and the engagement of said projection with the other cam serving to rotate the rod to a different degree to cause the other arm to operate the key-locking mechanism. 100

2. In a typewriting machine, the combination of a shiftable frame, a carriage mounted to travel in said frame and comprising a rear bar, a rod journaled in said frame, a margin-gage device adjustably mounted on said rod, arms fixed to said rod, one at each end thereof, a bell-ringing device mounted on said frame, a key-locking mechanism mounted on the machine, and a lever pivoted on said rear bar and extending therealong, 115 said lever being adapted to engage said margin-gage device to rotate said rod and cause one of said arms to operate the bell-ringing device and the other of said arms to operate the key-locking mechanism, successively. 120

3. In a typewriting machine, the combination of a shiftable frame, a carriage mounted to travel in said frame and comprising a rear bar, a rod journaled in said frame, a margin-gage device adjustably mounted on 125

- 5 said rod, a projection on said margin-gage device, arms fixed to said rod, one at each end thereof, a bell-ringing device mounted on said frame a key-locking mechanism 70
 10 mounted on the machine, and a lever pivoted on said rear bar and provided at one end with a double cam surface adapted to engage said projection, the engagement of said projection with the first of said cams serving 75
 15 to rotate said rod to cause one of said arms to operate the bell-ringing device, and the engagement of said projection with the second cam serving to rotate the rod to a different degree to cause the other arm to operate the key-locking mechanism. 80
- 20 4. In a typewriting machine, the combination of a shiftable frame, a carriage mounted to travel in said frame and comprising a rear bar, a rod journaled in said frame, a 85
 25 margin-gage device adjustably mounted on said rod, a projection on said margin-gage device, arms fixed to said rod, one at each end thereof, a bell-ringing device mounted on said frame, a key-locking mechanism mounted on the machine, a lever pivoted on said rear bar and provided at one end with a 90
 30 double cam surface adapted to engage said projection and at the other end with a finger-piece, a spring normally pressing said double cam surface downwardly into engagement with said projection, and a stop engaging said lever for limiting the downward movement thereof, the engagement of said projection with the first of said cams 95
 35 serving to rotate said rod to cause one of said arms to operate the bell-ringing device, and the engagement of said projection with the second cam serving to rotate said rod to a different degree to operate the key-locking 100
 40 mechanism, said finger-piece being operable against the action of said spring to rotate said double cam surface out of engagement with said projection to allow said arms to return to normal position. 105
- 45 5. In a typewriting machine, the combination of a shiftable frame, a carriage mounted to travel in said frame, a rod journaled in said frame, a margin-gage device adjustably mounted on said rod, an 110
 50 arm fixed to said rod, a bell-ringing device mounted on said frame, said device comprising a bell, a clapper pivoted on said frame, and a trip-lever pivoted on said clapper and capable of independent downward rotation but adapted to rotate upwardly integrally with said clapper, and means on said carriage adapted to engage said margin-gage device to rotate said rod and swing said arm upwardly, said arm being adapted to lie beneath said trip-lever and rotate said trip-lever and clapper upwardly against the action of said spring, 115
 55 said arm being adapted to slip past said trip-lever to allow said spring to return said trip-lever and clapper to lowered position and strike said bell, said arm being adapted to return to normal position beneath said trip-lever by rotating said trip-lever downwardly against the action of said spring and slipping past the trip-lever when the means on said carriage releases said margin-gage device, said spring restoring said trip-lever to normal position. 120
- 60 6. In a typewriting machine having type-keys and a universal bar actuatable by said keys, the combination of a shiftable frame, a carriage mounted to travel in said frame, a rod journaled in said frame, a margin-gage device adjustably mounted on said rod, an operating arm fixed to said rod, a bell-crank pivoted on said machine and having one arm thereof adjacent the universal bar and the other arm thereof terminating adjacent said 125
 65 130

operating arm, and means on said carriage adapted to engage said margin-gage device to rotate said rod and operating arm, said operating arm being adapted to engage the 5 adjacent arm of the bell-crank and rotate the latter about its pivot to position the other arm of said bell-crank beneath the universal bar and prevent actuation thereof.

9. In a typewriting machine having type-10 keys and a universal bar actuatable by said keys, the combination of a shiftable frame, a carriage mounted to travel in said frame, a rod journaled in said frame, a margin-gage device adjustably mounted on said rod, 15 an operating arm fixed to said rod, a bell-crank pivoted on said machine and having one arm thereof adjacent the universal bar and the other arm thereof terminating adjacent said operating arm, means on said carriage adapted to engage said margin-gage device to rotate said rod and operating arm, 20 said operating arm being adapted to engage the adjacent arm of the bell-crank and rotate the latter about its pivot to position the 25 other arm of said bell-crank beneath the universal bar and prevent actuation thereof, and a spring fixed to said machine and said bell-crank and normally holding the last-named arm of said bell-crank in ineffective 30 position to allow actuation of the universal bar.

10. In a typewriting machine having type-keys and a universal bar actuatable by said keys, the combination of a shiftable 35 frame, a carriage mounted to travel in said frame, a rod journaled in said frame, a margin-gage device adjustably mounted on said rod, an operating arm fixed to said rod, a bell-crank pivoted on said machine and

having one arm thereof adjacent the universal bar and the other arm thereof terminating in a cam surface adjacent said operating arm, and means on said carriage adapted to engage said margin-gage device to rotate said rod and operating arm, said 45 operating arm being adapted to engage said cam surface and rotate said bell-crank about its pivot to position the respective arm of said bell-crank beneath the universal bar and prevent actuation thereof. 50

11. In a typewriting machine having type-keys and a universal bar actuatable by said keys, the combination of a shiftable frame, a carriage mounted to travel in said frame, a rod journaled in said frame, a 55 margin-gage device adjustably mounted on said rod, an operating arm fixed to said rod, a bell-crank pivoted on said machine and having one arm thereof adjacent the universal bar and the other arm thereof terminating in a vertical cam surface adjacent 60 said operating arm, and means on said carriage adapted to engage said margin-gage device to rotate said rod and operating arm, said operating arm being adapted to engage 65 said vertical cam surface and rotate said bell-crank about its pivot to position the respective arm of said bell-crank beneath the universal bar and prevent actuation thereof, said vertical cam surface being of sufficient 70 height to insure contact of the operating arm therewith in the lowered and shifted positions of the frame.

ALFRED G. F. KUROWSKI.
